UNITED STATES PATENT OFFICE.

ROBERT HUNTER, OF LONDON, ENGLAND, ASSIGNOR, BY MESNE ASSIGNMENTS,
TO THE FARRAND & VOTEY ORGAN COMPANY, OF DETROIT, MICHIGAN.

ORGAN.

SPECIFICATION forming part of Letters Patent No. 487,222, dated November 29, 1892.

Application filed January 11, 1892. Serial No. 417,764. (No model.) Patented in England June 8, 1885, No. 6,946.

To all whom it may concern:

Be it known that I, ROBERT HUNTER, organ-builder, a subject of the Queen of Great Britain, residing at No. 65^a High Street, Clapham, 5 London, in the county of Surrey, England, have invented certain new and useful Improvements in the Manufacture of Wind-Organ^s, (for which I have obtained a patent in Great Britain, No. 6,946, bearing date the 8th 10 day of June, 1885;) and in what manner the same is to be performed is particularly described and ascertained in the following specification.

This invention relates to an improved means 15 of coupling the notes in an organ; and it consists in the construction and arrangement of parts hereinafter described and claimed, the object being to enable the player to sound two or more notes by depressing a single key, a 20 further object being to produce a uniform "touch"—that is, to cause the resistance to depression to be uniform throughout all the keys. For this purpose I divide the "swell" air-chamber into as many air-tight compartments or chambers as there are keys or notes 25 on the organ, the partitions being formed by metal plates fitting in grooves or channels in the back and front of the chamber, and into each of these compartments I lead a number 30 of air-tubes, each of which leads from the valve controlled by some one of the keys, the tubes leading into the compartment being those from the several keys which are to be coupled together. Over and behind the key- 35 board are placed two or more sound boards or chambers, within which are located the ends of the coupling-tubes and within which are also the valves or pallets that uncover these ends of the coupling-tubes. In connection 40 with these sound-boards are also sliding valves adapted to close any one or all of the coupling-tubes leading out from the sound-chamber.

The invention will be more fully understood by a reference to the drawings hereto attached, 45 in which—

Figure 1 shows in section the air-chambers and the coupling-tubes. Fig. 2 shows in sectional elevation the coupling-tubes and the manner of crossing them from the key of one 50 note to the chamber in the swell-box to be coupled with the note indicated by the key

struck. Fig. 3 is a sectional plan view of the swell air-chamber. Fig. 4 is a perspective, some of the coupling-tubes, however, being removed, leaving only enough of them completely shown to indicate the main features of the invention without obscuring the features by a multiplicity of parts.

A' represents a key, which operates the lever B' and opens the pallet E' against the closing force of the spring e'. The pallet E' is in the air-chamber or console G', and the opening of the pallet E' permits the air to escape into the tubes 9 10 11. Of these the tube 11 is in direct communication with the compartment L' in the swell-chamber H, and the compartment L' communicates through a tube l with the reed which sounds the note indicated by the key A'. The tube 10 leads to a compartment of H that is higher in tone than the note indicated by the key A', and the tube 11 leads to a compartment in the chamber H that sounds a note lower in tone. As indicated in the drawings, these tubes would couple three notes an octave apart; but of course 75 they may be arranged to couple octaves or thirds or any other combination that the builder may desire.

The key A², operating through the lever B, opens the pallet D and permits the air to escape from the console F through the tubes 1 2 3 into the swell-chamber H, acting similarly in all respects to the coupling of notes produced by the console G'. Leading out of the console F are also coupling-tubes 7 8, communicating with a second swell-box H', from which a second set of reeds is operated through the tubes l', so that by striking a single key A² it is seen that the operator sounds the notes of five different reeds, and the number may be increased indefinitely. Under each tube is a slide K, which is movable and which in one position closes the opening from the console into the tube and in another position admits the air freely into the tube from the console. The slide terminates in a handle k, by which the player can operate it.

The method of dividing the swell air-chamber is an important feature of my invention and is shown in Fig. 3. The back and front 100 walls of the chamber are grooved, and into the grooves are fitted plates L L, of metal, and

these are secured in place by the channels. Glue or other adhesive material is thus dispensed with and a perfectly-smooth surface is presented for the valve J. At the end of 5 each tube where it enters its proper compartment in the chamber H is a flat valve J J', which serves as a stop to prevent the air from returning to the sound-board or console, and thereby interfering with the other tubes or 10 putting other notes into play at times when they are not wanted.

It will be seen that any number of notes within reasonable limits may be sounded by the depression of one key, the actual number 15 of notes that may be sounded thus being limited by the number of tubes that lead out from above the pallet connected with any particular key and the number of tubes used at any time being governed by the position of the 20 slide K.

The console F above the pallet is divided into compartments similar to those in the swell-box.

What I claim is—

25 1. In an organ, the combination of a key, a

swell-chamber divided into compartments, one for each reed, and air-chamber with a valve or pallet therein operated by said key, two or more coupling-tubes leading from said pallet to different compartments of the swell- 30 chamber, and valves over the ends of the tubes and adapted to admit air by the depression of one key to two or more compartments of said swell-chamber, substantially as and for the purpose described.

2. In an organ, the combination of a swell-chamber having dividing-diaphragms secured within grooves in the front and back walls of said chamber and two or more coupling-tubes leading into a single compartment of said 40 swell-chamber and operated by different keys, substantially as and for the purpose described.

ROBERT HUNTER.
